(57) **CLAIM**

The ornamental design for a dash cam mount, as shown and described.

DESCRIPTION

FIG. 1 is a front perspective view showing a dash cam mount of the present invention;

FIG. 2 is a rear perspective view thereof;

FIG. 3 is a top view thereof;

FIG. 4 is a front view thereof;

FIG. 5 is a left side view thereof;

FIG. 6 is a right side view thereof;

FIG. 7 is rear view thereof;

FIG. 8 is a bottom view thereof; and,

FIG. 9 is a front perspective view.

In the drawings, the broken line showings are for purposes of illustrating environmental structure or portions of the dash cam mount that form no part of the claimed design.
